Attorney,

UNITED STATES PATENT OFFICE.

ANDREW STRAND, OF MINNEAPOLIS, MINNESOTA.

INTERNAL-COMBUSTION ENGINE.

Application filed December 2, 1920. Serial No. 427,770.

This invention relates to certain new and useful improvements in internal combustion engines and has for one of its objects the provision of removable piston receiving sleeves mounted in a single casing whereby uniform compression may be maintained in each cylinder.

Heretofore, internal combustion engines have had the cylinders which receive the piston cast with and forming a part of the casing, and in some instances removable liners have been provided for these cylinders, but it has been proved that in use of these types of engines, that when the compression in the cylinders becomes unbalanced, the entire engine must be dismantled and the cylinder re-bored or otherwise repaired, and when this is done it follows that the particular cylinder repaired will give greater efficiency than the others, and to overcome this as well as to obviate the laborious and expensive operation of dismantling the engine, I have provided a hollow casing having removable, piston receiving sleeves fitted therein, whereby should anyone of these piston sleeves prove faulty it only has to be removed and replaced by a new one, or if necessary the entire set of sleeves can be removed at a great deal less expense and labor than the repairing of the present type of engine; and further, the replacing of a whole set of sleeves guarantees a uniform compression by the engine.

A further object of this invention is the provision of a casing and removable piston carrying sleeves, which when assembled are constructed to provide a cooling medium chamber.

Another object of the invention is the provision of a casing having annular concentric seats therein, piston receiving sleeves fitted in said casing upon said seats, the walls of the sleeves and casing forming a cooling chamber, whereby the entire exposed area of the sleeve may be properly cooled.

Another object of the invention is the provision of a casing having spaced reinforcing ribs therein, which are provided with openings and communicate with a cooling chamber to permit the cooling fluid to freely circulate about the sleeve.

A still further object of the invention is the provision of a removable sleeve provided with spaced concentric seats, and

spaced re-inforcing ribs which constitute heat distributing members.

With these and other objects in view, the invention consists in certain novel features, combination and arrangement of parts as will be hereinafter more fully described and set forth in the claims hereto appended.

In the drawings,

Figure 1 is an end elevation and partly in section of the internal combustion engine, as made in accordance with this invention,

Figure 2 is a fragmentary longitudinal sectional view of the engine casing and sleeves,

Figure 3 is a fragmentary top plan view of the casing and sleeves,

Figure 4 is a vertical sectional view of the casing showing the sleeve and plan,

Figure 5 is a perspective view of one of the sleeves,

Figure 6 is a front elevation of the sleeve carrying casing, and,

Figure 7 is a part sectional front elevational view of a modification of the sleeves partly in section.

Referring to the drawings the numeral 5 indicates a hollow casing of my improved engine, and it is adapted and capable of being constructed for one or as many more piston receiving pockets as desired. This casing 5 is secured to the usual crank case 6, and has secured to its upper side the usual head 7, this head being equipped with an intake 8, exhaust 9, closed by the usual valves 10 and 11 respectively. These valves are operated through the medium of levers 12 which are in turn operated by cams 13 mounted on a shaft 14. The head 7 is provided adjacent the intake with a spark plug opening 15 which communicates with the usual compression chamber 16. The parts just described form no particular part of this invention other than to complete the engine and form a holding means for the removable sleeves which will be hereinafter more fully described.

The hollow casing 5 is cast in a single piece and is provided in its upper end with spaced openings 17 constituting pockets for the reception of removable piston carrying sleeves 18 and has inwardly directed flanges 50 thereon.

The casing is provided adjacent these openings with a spaced transversely extending and inwardly depending re-inforcing rib 19. The ribs and part of the casing

adjacent the upper open edge of the openings 17 are provided with seats 20', these seats being annular and are concentric with the seats 21 formed on the upper edge of the upwardly projecting annular wall 20 formed at the lower end of the cylinder of the casing 5. The wall 20 is annular and is formed at the bottom of the casing and coincides with the respective openings 17 to complete the pockets for the reception of the sleeves 18. The wall 20 projecting upwardly for a slight distance within the casing 5 forms a water chamber or other cooling medium pockets 22 and communicates with the chamber 23 formed by the wall of the casing and sleeves respectively. The reinforcing ribs 19 are provided with vertical and transverse intersecting openings 24 which establishes a communication 20 between the cooling chamber 23 and the various cooling chambers 25 in the head 7.

The casing 5 is provided in its side wall with a connection 26 which communicates with the water chamber 23 so that a pressure pump 27 may be used to force the cooling medium from the chamber 23 uniformly about the sleeves 18 and up into the various chambers 25 of the head 7.

It is to be understood that the casing 5 is cast from aluminum or other material suitable for the purpose, and in view of its construction it will be readily seen that it can be made of comparatively light material decreasing its weight without lowering its degree of strength or usefulness.

The sleeves 18 are cylindrical and as they are all identical in construction the description of one will serve for all. The sleeve is provided at its upper end with an annular exterior enlargement 28 which is reduced adjacent its upper edge as at 29 to form a vertical circumferentially extending exterior seat 30 and a horizontal seat 31. The seat 31 is adapted when the sleeve is fitted in the pocket 17 to engage the seats 20', while the seat 30 of the sleeve bears against the adjacent wall of the annular seat 20'. It is to be understood that the annular seats 20' of the casing and the seats 30 and 31 of the sleeves fit with such a nicety as to form a liquid tight joint so as to close the passage 23 so as to cause the water to circulate through the intersecting openings 24.

The sleeves are provided at an intermediate portion with an annular exterior flange 32 providing a seat 33 which is adapted to engage the seat 21 of the wall 20 so as to form with the seats at the upper edge thereof a rigid support for the sleeve. The portion of the sleeve below the flange 32 engages the wall 20 for its entire length, and thereby the sleeve is rigidly supported against any lateral movement relative to the casing 5. It will also be seen that the seats above mentioned together with the wall 20

prevent the sleeves from moving out of alignment and causing injury to the pistons moving therein.

The sleeve 18 is provided between the enlargement 28 and flange 32 with a plurality of spaced exteriorly arranged circumferentially extending heat distributing ribs 34 which ribs also serve to re-inforce the sleeve at a portion not engaged by the casing.

After the sleeves are placed within the casing 5 in the manner described and the head placed on the casing, the sleeves are ready to receive the usual reciprocating pistons 35 actuated therein by the piston rods 36 which are connected in the usual manner to a crank shaft 37.

It will be seen that an engine constructed in accordance with this invention will be one in which all of the sleeves will receive the same amount of cooling due to the fact that through the medium of the pump 27 the cooling fluid will be forced throughout the passage 23 and about the entire exposed surface of the sleeve.

The walls 20 are also provided with openings 38 which permit a free circulation of water from the pockets 22 into and about the lower ends of the sleeve.

It can be readily seen that if one of the sleeves 18 becomes worn or otherwise faulty it remains that it is only necessary to remove the head 7, renew the faulty sleeve, replace the head and the engine is ready for operation again. It may also be well to state that in view of the fact that the sleeves are removable that they can be constructed of steel or equivalent material, which gives them added strength and rigidity so as to increase their life for the purpose for which they are intended.

While in the foregoing there has been shown and described the preferred embodiment of this invention, it is to be understood that such changes may be made in combination and arrangement of parts as will fall within the spirit and scope of the invention as claimed.

What I claim as new is:

1. An engine comprising a casing having a wall formed to provide a water jacket, a second wall spaced from said first wall and integrally connected therewith at the lower portion thereof, said second inner wall extending upwardly and terminating at a point near the center of the outer wall, a flange formed in the upper portion of said outer wall, seats formed in said flange and in the upper portion of said inner wall and a removable sleeve seated within said seats.

2. An engine comprising a casing having a wall forming a water jacket, a flange issuing inwardly from said wall, a seat formed in said flange, a wall positioned within said jacket at the lower portion

thereof and spaced therefrom, said wall being connected to said jacket at its lower portion and a sleeve adapted to fit snugly within said interior wall having a shoulder 5 adapted to become seated in said engine flange seat.

3. An engine comprising a casing having a wall forming a water jacket, a flange issuing inwardly from said wall, a seat 10 formed in said flange, a wall positioned within said jacket at the lower portion thereof and spaced therefrom, a sleeve adapted to fit snugly within said interior wall having a shoulder adapted to become seated in 15 said flange seat, and packing means posi-

tioned at the extreme upper end of said inner wall engaging said sleeve for forming a water tight connection therewith.

4. An internal combustion engine comprising 20 a casing provided with transversally disposed strengthening ribs adjacent the upper edge thereof, annular seats formed in said ribs and casing, a spaced wall formed at the bottom of said casing and concentric with said seats, sleeves fitted in said casing and 25 engaging said seats and wall for the purpose specified.

In testimony whereof I affix my signature.

ANDREW STRAND.
